METHOD OF PACKING BULLETS

Robert William Vergobbi, Quincy, Mass., assignor to Pneumatic Scale Corporation, Limited, Quincy, Mass., a corporation of Massachusetts

Application March 19, 1943, Serial No. 479,683

2 Claims. (Cl. 86—47)

This invention relates to a method of packing bullets and other elongated articles of general cylindrical shape.

The invention has for an object to provide a novel and highly efficient method of packing bullets and other elongated articles of general cylindrical shape in a container such as a carton in a compact, predetermined and uniform arrangement.

With this general object in view and such others as may hereinafter appear, the invention consists in the method of packing the bullets and other elongated articles of general cylindrical shape and hereinafter described and particularly defined in the claims at the end of this specification.

In the drawing, Fig. 1 is a plan view of the bullet holding and transfer member, Fig. 2 is a side elevation of the same, Figs. 3 and 4 are perspective views illustrating successive steps in the present method of packing the bullets, and Fig. 5 is a perspective view of a filled container preparatory to being closed for shipment.

In general, the present invention contemplates a method of packing bullets for shipment in cartons and similar containers and is designed to facilitate the packing operation and to insure that the bullets are packed in the containers efficiently, with minimum waste of space and with the corresponding ends of the bullets pointing in a uniform direction.

Accordingly, the present method of packing bullets contemplates the use of a novel bullet holding and transfer member 10 comprising a base member 16 provided with a plurality of upstanding pins 18 arranged in spaced rows. The size of the pins 18 and the spacing of the same are related to the size of the bullet to be packed so as to enable bullets 12 to be assembled in the holding member with their lateral surfaces in contact and with a pin 18 disposed in the space 20 between four adjacent bullets as clearly shown in Fig. 1. In this manner, minimum space is wasted in the packaging of the bullets.

In practicing the present method the operator places the bullets with their pellet ends 21 downwardly in the pockets 20 formed between each set of four pins thus forming an assembly such as is illustrated in Figs. 1 and 2. The carton 14 is then inverted and slipped downwardly over the upstanding pins 18 and the bullets held thereby, into a position such as is illustrated in dotted lines in Fig. 3. The operator then inverts the whole assembly, removing the bullet holding and transfer member 10 as illustrated in Fig. 4, leaving all of the bullets packaged within the carton 14 in closely packed and contacting relation and in evenly spaced rows with the pellet ends up-

wardly. The carton may then be closed by flaps, including end flaps 22 which may and preferably will have folded portions 30 arranged to extend down between adjacent rows of the bullets as illustrated in Fig. 5 to further assist in confining the bullets and to prevent them from displacement during shipment. The upper flap 24 of the carton may be closed in any manner as by being adhesively secured to the horizontally extended end flaps 22 and by the tucking flap 25 which may be tucked inside the front wall 26 of the carton.

The present bullet holding and transfer member 10 finds particular use in connection with machines for orienting and handling bullets, such machines forming the subject matter of my applications, Serial No. 473,091, filed January 21, 1943, and Serial No. 473,092, filed January 21, 1943, to which reference may be made. Such machines may deliver properly oriented bullets in successive rows and such rows of bullets may be conveniently deposited in the present bullet holding and transfer member and thereafter packaged as above described.

Having thus described the invention, what is claimed is:

1. In a method of packing tapered bullets in a carton, the steps comprising arranging the bullets vertically with their smaller pellet ends pointing downwardly and with the peripheral surfaces of their larger cartridge ends in contacting engagement to form a compact mass of bullets, holding the bullets in such position by supporting them intermediate their tapered sides while maintaining the cartridge ends in peripheral engagement, placing over the bullets an inverted carton of a size such as to snugly fit the mass of bullets, and subsequently inverting the mass of bullets and the carton to effect disposition of the bullets in the carton.

2. The method of packing in a carton bullets of the type which taper from their larger cartridge ends to their smaller pellet ends comprising arranging the bullets vertically with their pellet ends pointing downwardly and with the cartridge ends in peripheral engagement to form a compact mass of bullets, laterally supporting the bullets below their contacting ends and intermediate the space formed between their tapered sides while disposed in such vertical position and with their cartridge ends in contacting engagement, placing an inverted carton over the bullets of a size adapted to snugly fit the mass, and then inverting the mass and the carton to dispose the bullets in the carton with their pellet ends uppermost.

ROBERT WILLIAM VERGOBBI.
